ABSTRACT: A sliding overhead door is normally maintained in its up position by means of at least two helical torsion springs arranged to apply torque to a rotatable shaft which in turn applies a lifting force to cables secured to the door. One of the torsion springs applies torque to the shaft through a heat-fusible connection whereby that torque is released upon fusion of the connection as the result of fire, to allow the door to close against the action of the remaining spring.

TEMPERATURE-ACTUATED OVERHEAD DOOR

DISCLOSURE

This invention relates to improvements in sliding overhead door structures of a type currently in use in industry and in homes. In particular the invention relates to torsion spring-supported overhead doors wherein the improvement resides in an arrangement which automatically operates to close the door in response to an increase in temperature caused by a fire in the vicinity of the door.

Conventional overhead door structures of the general type contemplated by this invention include a vertically slideable door together with a guide frame for the side edges of the door and a door suspension and support arrangement. The latter includes a horizontal rotatable drive shaft carrying on each end a threaded drum on which is wound a door-lifting cable. One end of each cable is secured to its respective drum, and the other end is secured to the lower portion of the door, so that when torque is applied to the drive shaft in the appropriate direction a lifting force is transmitted by the drums to the cables. One or more variable force torsion springs are arranged to apply lifting torque to the drive shaft, this lifting force being insufficient to raise the door from a closed position yet sufficient to aid materially in raising the door and to retain it in the full open position. Generally the torsion spring is mounted concentrically about the drive shaft with one end of the spring being secured to the drive shaft and the other end being fixed in position as by means of a bracket secured to an adjacent building wall.

The door itself may be rigid or formed in horizontal sections which are hinged together. In the former case the door moves only in a vertical plane, while in the latter case the door will usually be guided first upwardly and then rearwardly by means of suitable inclined guide tracks. Doors used in homes as garage doors are generally constructed of wood or metal. Doors used in industrial buildings may be constructed of materials adapted to resist the transmission of heat in the event of a fire.

The term torsion spring refers to a helical or spiral spring tensioned by winding about its axis so that the wound spring applies a force tangential to its axis. When a rotatable shaft is disposed along the axis, the tangential force becomes a torque tending to rotate the shaft. The magnitude of the force varies with the degree of windup.

So far as is known, overhead doors of the above-described type have not been adapted to close automatically in the event of a fire, although certain kinds of automatically closing fire doors are known. One type of such fire door in current use is a horizontally sliding door of rather massive construction mounted on an inclined track and maintained in the open position by a weight which holds the door at the higher end of the track by means of a cable and pulley arrangement. The cable includes a heat-fusible link which will melt in the event of a nearby fire, thereby disconnecting the weight from the door and allowing the latter to roll by gravity along the inclined track to a closed position. Such doors, intended to remain normally open, are usually of relatively great weight and the track is relatively steeply inclined to assure positive movement of the door, with the result that the door will generate considerable momentum and requires a massive frame to stop it at the lower end of the track. The momentum of the door is also hazardous to life and limb.

Another type of automatically closing fire door is disclosed in U.S. Pat. No. 3,345,775. In this arrangement a vertically movable rigid fire door is supported in an open position by means of a special assembly of two constant force coil band springs connected directly at one end to the door to effect a lifting action thereon. One of the connections includes a heat-fusible link capable of disconnecting its spring from the door to permit the latter to close against the action of the other spring.

The present invention, as previously stated, relates to a different type of door mechanism, that is a door mechanism in-

cluding at least one main torsion spring which applies torque to a rotatable drive shaft which in turn winds or unwinds a pair of door-lifting cables. The invention contemplates the combination of a main torsion spring or springs together with a low-torque auxiliary torsion spring which is releasably connected to the drive shaft by a suitable fusible link. The combination of springs provides sufficient counterbalancing force to hold the door up, but the mainspring or springs do not provide sufficient torque for this purpose, with the result that the door will close when the auxiliary spring is disconnected from the drive shaft.

The practical significance of the present arrangement is that it can be incorporated simply and economically in existing doors of the torsion spring type, or it can be incorporated during initial construction of such doors at little or no additional cost. The conventional framing and/or suspension arrangement need not be redesigned or modified, it being necessary only to employ a mainspring of lesser lifting power. The auxiliary spring may be incorporated into the suspension arrangement without any changes in the latter except partial disassembly in the case of an existing door structure. In the preferred embodiment the invention takes the form of an adapter for an existing door structure, the adapter including a bracket to be mounted to a fixed area adjacent the door for fixing one end of the low-torque auxiliary spring and further including the auxiliary spring together with means for connecting the other end of the latter to the drive shaft and a heat-fusible link capable of releasing the torque applied by the auxiliary spring to the drive shaft.

It will be understood that a heat-fusible link refers to any device which includes a solid material which has sufficient strength to effect a suitable mechanical connection and which will melt at a relatively low temperature to release the connection. Typical materials are various metal alloys having a melting point of about 150°F.

The invention will be further understood from the following detailed description of a preferred embodiment taken with the drawings in which:

FIG. 1 is a rear elevational view of an overhead door structure embodying the principles of the present invention; and

FIG. 2 is an enlarged perspective view of the auxiliary spring assembly of FIG. 1.

The door structure of FIG. 1 includes an overhead sectional door 10 having its side edges guided by two spaced-apart guide members 12 in the form of inwardly-facing channels which are adapted to receive rollers 14 or the like, the latter being carried by the side edges of the door. The door 10 is constructed of horizontal sections 16 or panels hinged together in conventional manner to permit the door to flex into an inclined position when it is moved upwardly to its full open position, as determined by the inclined upper portions of the guide members 12. The latter are secured to the wall of the building or to any fixed supporting structure 15, as by means of brackets 17.

A mechanism for assisting in supporting the weight of the door 10, so that it can be raised and lowered by the application of relatively small force, includes a pair of lifting cables 18 attached at one end to the lower portion of the door 10 as by brackets 20 near the latter's side edges and attached at their other ends to exteriorly threaded drums 22 in a manner to be wound thereon. The drums 22 are fixed to the opposite end portions of a horizontal rotatable drive shaft 24 which is disposed above the door 10 when it is in a closed position. The ends of the shaft 24 project through the drums 22 and are mounted for rotation within brackets 26 which are fixed to the supporting structure 15 as by screws 28. At least one main torsion spring assembly 30 is associated with the drive shaft 24 in a manner to apply a torque thereto in a direction to wind up the lifting cables 18, thereby applying a lifting force to the door 10. In the conventional arrangement the spring assembly 30 applies maximum lifting torque when the door is down and completely counterbalances the door 10 when it is fully open so that it will remain open until a small positive force in the opposite direction is applied.

75

All of the above is conventional in overhead door structures of the torsion spring-type and has been described in order to place the present invention in its proper environment. The system illustrated in FIG. 1, in order to be automatically closable in response to a temperature rise, embodies two features which are not present in a conventional system. First, the main torsion spring assembly 30 is modified to the extent that it will not counterbalance the door 10 when in the fully open position. Second, there is provided an auxiliary torsion spring assembly 32 which applies sufficient torque to the drive shaft 24, through a heat-releasable connection, that both spring assemblies together will maintain the door open. Accordingly, the main torsion spring assembly 30 requires a spring of lesser torque characteristics than the originally designed spring. Usually a spring which applies 50 pounds less force is satisfactory. In practice the weaker spring is employed as original equipment when the invention is applied to a door manufacturing operation. When an existing door is being modified to incorporate the invention, the original spring is generally replaced with the weaker spring, although it may sometimes be feasible to adjust the original spring in a manner to produce less force.

In either event the mainspring assembly 30 may be operatively connected to the drive shaft 24 in any conventional manner. Usually the assembly includes a so-called winding plug 34 which is a sleeve-like element adapted to be slid over the shaft 24 and secured thereto as by means of one or more setscrews 36. A helical torsion spring 38 is also slid over the shaft 24, and one end of the spring is fixed to the plug 34 in a tangential position. The opposite end of the spring 38 is held in a fixed position, as by means of a suitable bracket 40 which is attached to a support pad 42 on the adjacent wall or other fixed area. After assembly of these parts, with the setscrews 36 being loose, the spring 38 is wound up in the appropriate direction by rotating the plug 34 relative to the shaft 24, this being accomplished manually by inserting a rod-like tool in any of several radial holes 44 in the plug 34 and using the tool as a lever to turn the plug 34. When the correct tension has been wound into the spring 38, the setscrews 36 in the plug 34 are tightened against the shaft 24 whereupon the spring 34 exerts a torque on the shaft 24 when the winding tool is removed.

The auxiliary spring assembly 32, as described previously, includes a relatively small torsion spring 46, which is adapted to be included either at initial manufacture of the door system or to be added subsequently, together with mounting means for attaching the spring 46 to the shaft 24 in a heat-releasable manner. As shown, the spring 46 is a spiral or clock-type spring rather than a helical spring, although the latter type may be employed if desired. The inner end of the spring 46 terminates in an inwardly projecting arm 48 which is force fitted into a complementary slot in the surface of a sleeve 50. The sleeve 50 is mounted on the drive shaft 24 and is fixed thereto as by means of one or more setscrews 52 which are axially offset from the spring 46. The outer end of the spring 46 is adapted to be held in a fixed position as by means of a suitable mounting bracket 54 which in the final door assembly is secured to the adjacent wall or other fixed area by screws 56 or the like.

The heat-releasable connection between the auxiliary spring 46 and the drive shaft 24 may take various forms. As shown, the outer end of the spring 46 is connected to the bracket 54 by means of a heat-fusible link 58 one end of which is hooked through a hole in the spring 46 and the other end of which is secured to the bracket 54 by a screw 60. Alternatively the inner end of the spring 46 may be connected to the sleeve 50 by a heat-fusible link, or the sleeve 50 can be keyed or otherwise drivingly connected to the shaft 24 with heat-fusible material.

In the preferred embodiment, the lifting capacity of the auxiliary spring 46 should not exceed 50 pounds as this is considered a safe industrial standard that an average person could lift in an emergency or in normal operating conditions. However, the lifting capacity of the auxiliary spring 46 can vary to

meet the needs of different door systems. The total door weight in the up position is equal to the combined spring tensions of the mainspring 38 and the auxiliary spring 46. It is seen, as an example, that if the door weight is 500 pounds, and the auxiliary spring 46 has a tension of 50 pounds, the main torsion spring 38 should have a tension of 450 pounds so that the combined force of the springs is sufficient to counterbalance the door 10.

In operation, when the temperature in the area of the door reaches a predetermined value which will melt the fusible link 58, the latter will come apart or separate, breaking the tension connection of the auxiliary spring 46 to the mounting bracket 54 and thereby releasing the torque applied by the spring 46 to the shaft 24. The force exerted by the main torsion spring or springs 38 is not sufficient to counterbalance the weight of the door 10, and the door will descend downwardly in the guide members 12 into a closed position. However, the door may be lifted manually with a small amount of effort equal to the force which was previously exerted by auxiliary spring 46. It should be noted in this type of construction, that spring length and tension of the spring will increase with each foot of door height.

The invention has its greatest utility in an industrial environment where relatively large areas are separated from each other by one or more overhead doors, the closing of these doors in the event of fire being highly desirable in order to reduce cross draft. The automatic closing feature does not introduce any hazard to persons in the area, because the force of the main torsion spring assembly is sufficient to prevent the door 10 from closing so fast as to cause injury. On the other hand as described above, the door 10 can be opened easily, because the main spring assembly continues to apply all but, say 50 pounds of the force necessary to lift the door 10.

As previously stated, the invention may be utilized during initial manufacture of a door system or utilized subsequently to modify an existing door, and in either case no costly departure from conventional construction is involved. When an existing door is to be modified it is necessary only to partially disassemble the door mechanism to the extent of removing the drive shaft 24 so that the sleeve 50 of the auxiliary spring assembly 32 may be slid over the shaft 24. The latter is then reinstalled, after substituting a weaker main spring 38, and the auxiliary spring 38 is wound up to the proper tension, using the previously-described conventional technique. It is contemplated that the auxiliary spring 46 in the assembly 32 may be prewound, in which event no winding is required at the time of installation.

I claim:

1. A door structure comprising: a frame having parallel guide members; a door mounted for sliding movement in said guide members; a rotatable shaft mounted in proximity to said guide members; means associated with said rotatable shaft for transmitting torque on the shaft to a lifting force on said door; a plurality of variable force torsion springs, each of said variable force torsion springs, each of said variable force torsion springs having one end mounted on said rotatable shaft and the other end secured to fixed means, said plurality of variable force torsion springs exerting a combination torque sufficient to counterbalance said door when in the full open position, the torque of either spring alone being insufficient to maintain said door open, and one of said variable force torsion springs being an auxiliary spring exerting a torque substantially less than said other variable force torsion spring; and heat-fusible connecting means between said auxiliary spring and said shaft for disconnecting the torque produced by said auxiliary spring at a predetermined temperature whereby said door will close in response to fusion of said connecting means.

2. A door structure as described in claim 1 wherein said means associated with said rotatable shaft comprises a threaded drum fixedly secured to said rotatable shaft and a cable having one end secured to said threaded drum with the other end being secured to said door.

3. A door structure as described in claim 1 wherein said auxiliary spring is a spiral clock-type spring.

4. A door structure as described in claim 3 wherein said clock-type spring has one end mounted to said rotatable shaft by suitable means and its other end connected to a mounting bracket by a fusible link.

5. A temperature-sensitive adapter for initiating closing movement of an overhead door of the type having a rotatable drive shaft, means connecting the drive shaft to the door in a manner such that rotation of the drive shaft is accompanied by upward or downward movement of the door, and main torsion spring means associated with the drive shaft to apply torque thereto in a lifting direction opposite to the torque produced by the weight of the door, said adapter comprising: an auxiliary torsion spring wound around a spring-supporting sleeve; first connecting means between the inner end of said auxiliary

spring and said sleeve; a mounting bracket adapted to be secured to a fixed area adjacent the drive shaft of the door structure; second connecting means between the outer end of said auxiliary spring and said bracket whereby said auxiliary spring when in a wound condition is capable of exerting torque on said sleeve; third connecting means associated with said sleeve for connecting said sleeve in concentric relationship to the drive shaft in a manner such that torque applied to said sleeve is transmitted to the drive shaft; and a heat-fusible member forming a part of one of said connecting means whereby upon fusion of said member the torque of said auxiliary spring will be released from the drive shaft to permit the door to close.
